UNITED STATES PATENT OFFICE

106,648

DESIGN FOR A WICKER BASKET

Tay-Wu Chien, San Francisco, Calif.

Application August 6, 1937, Serial No. 70,867

Term of patent 7 years

To all whom it may concern:

Be it known that I, Tay-Wu Chien, a Chinese citizen, residing in the city and county of San Francisco, State of California, have invented a new, original, and ornamental Design for Wicker Baskets, of which the following is a specification, reference being had to the accompanying drawing, forming part thereof,

Fig. 1 is a plan view of a wicker basket showing my new design.

Fig. 2 is a side elevation of a wicker basket showing my new design.

I claim:

The ornamental design for a wicker basket, as shown.

TAY-WU CHIEN.
